(57) **CLAIM**

The ornamental design for a surface configuration of a vehicle, toy, and miscellaneous consumer products incorporating the design, as shown and described.

DESCRIPTION

FIG. 1 is a left, front perspective view of a surface configu-

ration of a vehicle, toy, and miscellaneous consumer products incorporating the design according to our novel design;

FIG. 2 is a right, front perspective view of the surface configuration of a vehicle, toy, and miscellaneous consumer products incorporating the design according to our novel design;

FIG. 3 is a front view of the surface configuration of a vehicle, toy, and miscellaneous consumer products incorporating the design according to our novel design;

FIG. 4 is a left side view of the surface configuration of a vehicle, toy, and miscellaneous consumer products incorporating the design according to our novel design;

FIG. 5 is a right side view of the surface configuration of a vehicle, toy, and miscellaneous consumer products incorporating the design according to our novel design;

FIG. 6 is a left, rear perspective view of the surface configuration of a vehicle, toy, and miscellaneous consumer products incorporating the design according to our novel design;

FIG. 7 is a right, rear perspective view of the surface configuration of a vehicle, toy, and miscellaneous consumer products incorporating the design according to our novel design;

FIG. 8 is a rear view of the surface configuration of a vehicle, toy, and miscellaneous consumer products incorporating the design according to our novel design; and,

FIG. 9 is a top view of the surface configuration of a vehicle, toy, and miscellaneous consumer products incorporating the design according to our novel design.

The broken lines included depict environment and are not part of the claimed design.
